UNITED STATES PATENT OFFICE.

EPHRAIM POTTER, OF BOWLING GREEN, KENTUCKY.

FENCE.

SPECIFICATION forming part of Letters Patent No. 398,974, dated March 5, 1889.

Application filed September 15, 1888. Serial No. 285,491. (No model.)

To all whom it may concern:

Be it known that I, EPHRAIM POTTER, a citizen of the United States, residing at Bowling Green, in the county of Warren and State of Kentucky, have invented certain new and useful Improvements in Fences; and I do declare the following to be a full, clear, and exact description of the invention, such as will enable others skilled in the art to which it appertains to make and use the same.

This invention has relation to improvements in fences; and it consists in the peculiar construction, novel arrangement, and adaptation of parts, as will be hereinafter more fully set forth, and particularly pointed out in the claim annexed.

The invention will be more fully understood from the following description and claim when taken in connection with the annexed drawings, in which—

Figure 1 is a side view of fence constructed according to my improvements, and Fig. 2 is a plan view of the same.

In carrying out my invention I take panels *a*, which may be of the ordinary construction, having the vertical rails at each end provided with a plain outer side, so that when two of the panels are brought together they may fit each other snugly, as shown.

It should be observed that the longitudinal rails have their opposite ends fastened on the inside of one vertical post or rail and on the outside of the other in each section or panel, and that the side of the said vertical rail that receives the longitudinal rails is beveled, as shown at *a'*, so that the longitudinal rails of the panel, as well as the vertical rails, may meet snugly when they are united by means of transverse bolts *b* and nuts or other fastening devices.

Alternating in a staggering position with the panel-posts are vertical posts *A*, which are

of a much greater height than the said panel-posts, and are set a sufficient distance in the ground.

45
B and C indicate crown-wires, which are arranged in a peculiar manner, the wires B starting from the panel-post at one end of the fence, where the said wire is stapled and is connected with every alternate set of panel-
50 posts by means of staples *b*, which are driven in the tops of the said posts. The wire C, which is arranged longitudinally and intermediate of the lateral wires B, has its ends, by means of staples, secured to the intermediate tall posts, *A*, and this wire C is at a much greater elevation than the wires B, thereby affording a protection to the fence both in a lateral and top position. As the panels form a zigzag fence, the crown-wires will form a filling both on top and at the sides of each bend. It is obvious that these wires may have barbs placed upon them, in which case I would have a combined barb and rail fence at a very small expense.

55
Having described my invention, what I claim is—

60
The combination, in a zigzag fence, of tall posts alternating with the main fence-posts and arranged in line with each other, outer wires arranged, as shown, parallel to each other and to the middle wire and secured to the main fence-posts, so as to cross the bends or zigzags, the intermediate wire being arranged at a greater altitude than the outer
70 ones and secured to the alternating tall posts, substantially as specified.

75
In testimony whereof I affix my signature in presence of two witnesses.

EPHRAIM POTTER.

Witnesses:

W. E. SETTLE,
JOHN DURKEE.
